CONTROLS FOR PIPE DRIFTING MACHINES

William M. McConnell, McKeesport, Pa., assignor to Taylor-Wilson Manufacturing Company, McKees Rocks, Pa., a corporation of Pennsylvania

Application November 25, 1957, Serial No. 699,880

3 Claims. (Cl. 318—286)

This application is a continuation-in-part of my co-pending application Serial No. 419,889 filed March 30, 1954.

My invention relates to controls for pipe drifting machines and more particularly, to a control which is actuated by and regulates the advancement of a drifting mandrel through a length of pipe.

In the production of commercial pipe and tubing, manufacturers customarily pass a drifting mandrel through each length of pipe or tubing to make certain that each length of pipe has a specified minimum inside diameter and that there are no obstructions inside the pipe or tubing. Generally, these pipe drifting machines comprise a drifting mandrel which consists of a mandrel bar and a mandrel head on the bar corresponding to the inside diameter of the length of pipe being tested. The mandrel head is connected to one end of the mandrel bar. A pinch roll stand advances the drifting mandrel through the full length of the pipe and withdraws the drifting mandrel after the test. Pipe drifting machines heretofore known have required an operator to follow carefully, the advancement of the drifting mandrel through the pipe so that he can stop it when the mandrel has reached the end of the pipe and reverse the pinch roll stand to withdraw the drifting mandrel.

For efficient production of large tonnages of pipe it is highly important that these pipe drifting machines be fully automatic in that the pinch roll stand automatically reverses and withdraws the drifting mandrel when it has reached the end of a pipe and that each pipe is drifted its entire length.

My invention provides a pipe drifting machine control which accurately determines when the drifting mandrel has reached the end of a pipe and then automatically reverses the pinch roll stand thereby withdrawing the drifting mandrel. This control functions on pipes of any lengths. My pipe drifting control utilizes the advancement of the drifting mandrel through a length of pipe to stop and reverse the pinch roll stand at the moment when the drifting mandrel reaches the end of the pipe. More specifically, I employ in a pipe drifting machine having a drifting mandrel and means for reciprocating the drifting mandrel, a control comprising means for determining the amount of advancement of the mandrel through a pipe. Connected thereto is a signal generating means which controls the means for reciprocating the drifting mandrel.

In the accompanying drawings I have described a preferred embodiment of my invention in which:

Figures 1 and 1A comprise a plan view of a pipe drifting machine equipped with my control;

Figure 2 is an end view along the line II—II of Figure 1;

Figure 3 is a sectional view along the line III—III of Figure 1; and

Figure 4 is a diagram of electric circuits used in my control.

Figures 1 and 1A show a pipe drifting machine em-

2

bodying my invention which machine has a conventional pinch roll stand 1 which advances a drifting mandrel 2 through a length of pipe until the drifting mandrel reaches the end of the pipe. Then electric motor 3 which drives the pinch roll stand is reversed and the drifting mandrel is withdrawn from the pipe. The drifting mandrel comprises a mandrel bar 4 and a mandrel head 5 attached to the leading end of the mandrel bar 4. The mandrel head corresponds to the specified inside diameter of the length of pipe. A pipe handling table 6 supports the length of pipe to be drifted and a conventional pipe coupling screw on machine 7 holds the length of pipe in position on the pipe handling table and screws on a coupling on the pipe at the same time that the pipe is being drifted. Both the coupling screw on machine 7 and the pipe handling table 6 are aligned with the pinch roll stand and the drifting mandrel so that the drifting mandrel may be readily reciprocated inside the length of pipe.

20 As shown in Figures 1 and 3, a drift table 8 supports the mandrel bar 4 in a sleeve 9 through which the mandrel bar slides. Positioned adjacent the end of the mandrel bar 4 when it is in its retracted position, Figure 3, is a stop 10 which prevents overtravel of the mandrel bar towards the right, viewing Figure 3.

25 As shown in Figures 1 and 3 my pipe drifting machine control comprises a drum positioned adjacent the stop 10. This drum 11 is mounted upon a shaft 12 rotatable in bearings 13 and 13a. Wound upon the drum 11 is a cable 14 which has one end connected to the trailing end of mandrel bar 4 so that advancement of the mandrel bar through a length of pipe unwinds the cable from the drum and rotates the shaft 12. Connected to the shaft 12 through a gear reducer 15 is a conventional torque motor 16 which exerts a continual rotational force upon the shaft 12 opposing unwinding of the cable. After a pipe has been tested and while the drifting mandrel is being withdrawn from the pipe, the torque motor 16 winds up the cable upon the drum and keeps the cable taut during this operation to prevent fouling of the cable. During advancement of the drifting mandrel through the pipe the torque motor 16 exerts a continual back tension force upon the cable thereby keeping the cable taut and preventing fouling. The torque motor 45 is stalled during advancement of the drifting mandrel and also when the mandrel bar is against the stop 10, Figure 3.

50 Rotation of the shaft 12 resulting from unwinding the cable 14 from the drum drives a second gear reducer 17 which in turn rotates spindle 18 connected to the rotor of a synchro generator 19. The drum 11, shaft 12 and the second gear reducer 17 accurately and continually measure the amount of advancement of the drifting mandrel and transmit this amount of advancement to the synchro generator 19. The ratio of the gears in the sections of the drum 11 is reduced in the order of about 14 to 1 so that a substantial advancement of the drifting mandrel is equal to approximately one-half of one revolution of the rotor of the synchro generator. Thus the amount of rotation of the motor of the synchro generator is proportional to the amount of advancement of the drifting mandrel.

55 As shown in Figure 4 an A.C. excitation bus line 20 supplies power to the synchro generator. Connected to the synchro generator is a synchro transformer 21 to which is connected a conventional electronic amplifier 22. A magnetic amplifier is interchangeable with the electronic amplifier. The excitation bus line also supplies power to the electronic amplifier 22. The electronic amplifier 22 actuates a relay 23 which controls the operation of the pinch roll stand 1 through cam limit switch 26 con-

nected thereto and itself connected to the armature of the motor 3 to reverse the pinch roll stand when the drifting mandrel has reached the end of the length of pipe.

It is well known that when the rotors of the synchro generator and of the synchro transformer are in the same angular position or in positional agreement the voltage across the rotor of the synchro transformer is zero and when they are not in the same angular position there is a voltage across the rotor of this synchro transformer. By rotating the rotor of the synchro transformer to place it in a different angular position from that of the rotor of the synchro generator I cause a voltage on the leads 24 and 25 connecting the synchro transformer to the electronic amplifier. It is this voltage or the absence thereof across the leads 24 and 25 which I employ to control the operation of the pinch roll stand.

The operation of my pipe drifting machine control is substantially as follows. First, I set the pipe drifting machine to travel a distance corresponding to the length of the pipe in question by turning the rotor of the synchro transformer to a position corresponding to the length of the pipe and there locking it in position. The amount of co-rotation of the rotor is less than 180° out of positional coincidence with the rotor of transmitter 19. Three factors determine the amount of rotation of the rotor of the synchro transformer 21. These are the length of the pipe to be drifted, the diameter of the drum 11 and the ratio of the number of revolutions of the drum 11 to the number of revolutions of the rotor of the synchro generator 19. This rotation of the rotor of the synchro transformer places it in a different angular position from that of the rotor of the synchro generator and thereby causes a voltage across the leads 24 and 25.

Next I close push button 29 or cause relay 28 to close by delivering a length of pipe to the pipe drifting machine which pipe, upon delivery to the machine, trips a switch (not shown) controlling the relay 28. Closing either the push button 29 or the relay 28 connects the voltage across leads 24 and 25 to the amplifier 22, whereupon the amplifier is energized and closes a normally open relay (not shown) therein. When the amplifier 22 is actuated, either the closed push button 29 or the closed relay 28 opens.

Closing the normally open relay in the amplifier 22 energizes relay 23 which has three contacts 30, 31, and 32. Contacts 30 and 32 are normally open and contact 31 is normally closed so that when relay 23 is energized, contacts 30 and 32 close and contact 31 opens. Contact 30 controls a circuit connected to the electric motor 3 so that when it is closed, the motor advances the drifting mandrel 2 through a length of pipe. Contact 31 controls an electric circuit connected to the electric motor 3 so that when it is closed, the motor 3 reverses and returns the drifting mandrel to its starting position. Contact 32 breaks the electrical connection between the synchro transformer 21 and the amplifier 22 when the relay 23 is deenergized. As shown, contacts 30 and 31 are connected to the bus line 20.

During advancement of the drifting mandrel the amount of this advancement is accurately and continually measured by the drum 11 and the second gear reducer 17 which rotates the rotor of the synchro generator an amount proportional to the amount of advancement of the drifting mandrel. The rotation of the rotor of the synchro generator transmits a signal to the stator of the synchro transformer. This rotation of the rotor of the synchro generator continues until the rotor of the synchro generator and the rotor of the synchro transformer are once again in the same angular position at which time the voltage across leads 24 and 25 connecting the synchro transformer to the electronic amplifier is zero. When the rotor of the synchro transformer and the rotor of the synchro generator are once again in the same angular position, the drifting mandrel has advanced an amount equivalent to the length of the pipe. The amount of advancement of the drifting mandrel 2 as measured by the rotor of the synchro generator 19 corresponds to the

amount of rotation of the rotor of the synchro transformer 21 when the rotor of the synchro transformer was set at the start of the drifting operation.

When the voltage across leads 24 and 25 is zero, the amplifier 22 deenergizes whereupon the relay in the amplifier opens, thus causing relay 23 to deenergize. De-energization of relay 23 causes contacts 30 and 32 to open and contact 31 to close. Opening contact 30 halts advancement of the mandrel and opening contact 32 electrically disconnects the synchro-transformer from the amplifier 22. Closing contact 31 causes the motor 3 to reverse and withdraw the drift mandrel. The drifting mandrel continues to withdraw until it reaches its starting position, whereupon a normally closed contact (not shown) in cam limit switch 26 opens and interrupts the reverse control circuit of the motor 3. The drifting mandrel then remains at its starting position until either push button 29 or relay 28 closes.

The cam limit switch 26 which is connected to the second gear reducer 17 through spindle 27 also functions as a safety device to prevent overtravel of the drifting mandrel in the event the synchro transformer and synchro generator fail to operate. This cam limit switch is connected to conventional electric circuits (not shown) which control the operation of the pinch roll stand if the synchro transformer and synchro generator fail. The cam limit switch reverses the pinch roll stand after a predetermined amount of advancement of the drifting mandrel over and beyond the length of the pipe in question.

Since my invention accurately controls the amount of advancement of the drifting mandrel it is highly useful to manufacturers of large tonnages of pipe and tubing, in that delivery of pipe is not unnecessarily delayed by the drifting operation. My control permits a pipe manufacturer to efficiently drift large tonnages of pipe irrespective of whether they are the same size or varied sizes. The operator has only to set the control for the length of pipe to be drifted and then wait for the next pipe while the machine automatically performs the entire operation. If the next pipe has a different length, the operator merely changes the setting of the control to take into account the change in length. He does not have to move from his station at the control to make any adjustment on the drifting apparatus to take into account a different length of pipe. Pipe manufacturers need no longer rely upon the ability of a pipe drifting machine operator to reverse the pinch roll stand when he believes the drifting mandrel has reached the end of the pipe. Therefore, it is apparent that my control is especially useful for the automatic production of large tonnages of pipe.

While a certain present preferred embodiment of my invention has been shown and described, it will be understood that it may be otherwise embodied within the scope of the appended claims.

I claim:

1. In a pipe drifting machine, the combination comprising a drifting mandrel, means for reciprocating said drifting mandrel on said machine, a rotatable drum, a cable wound upon said drum and having one end connected to said drifting mandrel so that advancement of said drifting mandrel rotates said drum, means operated by rotation of said drum for determining the amount of advancement of said drifting mandrel, signal generating means actuated by said means operated by rotation and means responsive to a signal from said generating means for controlling said means for reciprocating said mandrel.

2. In a pipe drifting machine, the combination comprising a drifting mandrel, means for reciprocating said drifting mandrel on said machine, a rotatable drum, a cable wound upon said drum and having one end connected to said drifting mandrel so that advancement of said mandrel rotates said drum, means operated by said drum for determining the amount of advancement of said drifting mandrel, a synchro-generator actuated by

said means operated by said drum, a synchro-transformer electrically connected to said synchro-generator, and means responsive to said synchro-transformer for controlling said means for reciprocating said mandrel.

3. In a pipe drifting machine, the combination comprising a drifting mandrel, means for reciprocating said drifting mandrel on said machine, a rotatable drum, a cable wound upon said drum and having one end connected to said mandrel so that advancement of said mandrel rotates said drum, means connected to said drum for maintaining tension upon said cable during advancement of said mandrel and for winding up said cable during

return of said mandrel, means operated by said drum for determining the amount of advancement of said mandrel, a synchro-generator actuated by said means operated by said drum, a synchro-transformer electrically connected to said synchro-generator, and means responsive to said synchro-transformer for controlling said means for reciprocating said mandrel.
